Application January 19, 1935, Serial No. 2,474

10 Claims. (Cl. 230—214)

Our invention relates to devices which may be used for the compression of air and other gases, as well as for the pumping of fluids and for various other purposes which will be readily apparent to those skilled in the art.

An object of our invention is to provide a device of the class described which will be of high capacity as compared to its size and weight without sacrifice of strength.

10 A further object is to provide such a device which will be economical in construction and operation and will be sufficiently rugged to be capable of operation over long periods of time with a minimum of attention.

15 Various other objects and advantages will become apparent as the description proceeds.

Referring to the drawings forming part of this specification and illustrating certain preferred embodiments of our invention:—

20 Figure 1 represents an axial sectional view of one embodiment of our invention.

Figure 2 is a transverse sectional view taken substantially along the line 2—2 of Figure 1.

25 Figure 3 is an elevation looking from a position to the left of Figure 1.

Figure 4 is a sectional view taken substantially along the line 4—4 of Figure 3.

30 Figure 5 is a sectional view taken substantially along the line 5—5 of Figure 2.

Figure 6 is a perspective view showing a sealing bar and a cooperating spring therefor, constituting elements of our invention.

35 Figure 7 is a sectional view taken substantially on the line 7—7 of Figure 2.

Figure 8 is a perspective view of a sealing block constituting an element of the construction.

40 Figures 9, 10, and 11 are diagrammatic views showing the mechanism of Figs. 1—12 at various stages of its operation.

45 Figure 12 is a transverse sectional view, corresponding to Figure 2, showing a valveless modification of our invention, said section being taken along line 12—12 of Fig. 13;

Figure 13 is an axial sectional view of the same, taken along line 13—13 of Fig. 12.

50 Figure 14 is an axial sectional view of a cam and shaft constituting elements of the same construction, said section being taken on a plane rotated about 90 degrees from the position of Figure 13.

Figure 15 is a sectional view taken substantially along the line 15—15 of Fig. 12.

55 Figure 16 is a transverse sectional view corresponding to those of Figures 1 and 12, showing still another valveless modification.

Figure 17 is a sectional view taken substantially on the line 17—17 of Figure 16.

Figure 18 is a perspective view of a cam constituting an element of the same, and

5 Figure 19 is a developed plan view of the surface of said cam.

The improved mechanism may be supported as by means of an angular bed plate 10, which is secured as by means of threaded bolts 11 or the like to a cylindrical casing 12 which is preferably integral with a frame member 13. The frame 13, a similar cooperating frame member 13' and a hollow interposed frame member 14 constitute a housing H. It will be noted that the frame members 13, 13', and 14 are substantially similar in contour, and are secured together as by means of bolts b and define a rectangular chamber 15. The frames 13 and 13' have smooth faces f, f' against which frame member 14 seats snugly (Fig. 1). The frame members 13 and 13' are preferably reinforced on the outer faces thereof, as by means of a marginal flange g and transverse ribs r.

Disposed in the cylindrical casing 12 is a shaft 16 which is journaled in said casing 12 by means of two sets of ball bearings, indicated at 17 and 17', said bearings being maintained in longitudinally spaced relation relative to the shaft 16 as by means of a sleeve 18. The casing 12 is closed adjacent one end as by means of a cap 20 which may be secured to cylindrical part 12 as by bolts 21. The cap defines a chamber 22 for accommodating a lock nut 23 which is threaded onto the shaft 16 for retaining the same in proper longitudinal position. Said lock nut may be provided with apertures 24 registering with similar apertures in shaft 16, into which fits a circular spring wire 24' which functions somewhat as a cotter pin for retaining the nut in position. Cap 20 may also have an annular cavity 25 for retaining packing. The cylindrical casing 12 may also be provided with a normally plugged threaded opening 26 for introducing lubricant into the mechanism.

Formed integrally with the shaft 16 is a disk 30, apertures 28 being provided adjacent said disk for passage of lubricant. Disk 30 carries a crank or eccentric 31, which may be integral therewith, said crank 31 being disposed within the chamber 15. The crank 31 is pivotally mounted within a journaling portion 35 of a piston P, ball bearings or other suitable anti-friction devices 37 preferably being provided.

As seen best in Figures 1 and 2, the member P, which is referred to for convenience as a "piston" 55

because of its function, is a rectangular member which is preferably cut out as at *c* and *c'* in order to save weight and material. The side walls of said piston *P* (Fig. 4) are preferably cut out to 5 form longitudinal chambers *40*, the connecting wall *41* between said chambers being also removed adjacent the top and bottom of said piston (Fig. 5). These chambers accommodate sealing bars *43* which extend longitudinally of the 10 chambers and are provided with integral legs *44*. Disposed between said bars and the wall *41*, separating the chambers *40*, are strip or wave springs *46*, said springs also being provided with angular legs *47* so as to be of substantially the 15 same shape as the bars *43*. It will be seen that these bars are urged by their respective adjacent springs into close contact with the inner walls *f*, *f'* of the frames *13* and *13'* so as to serve as seals to prevent passage of fluid. Hence, said 20 devices function similarly to piston rings in the ordinary cylindrical piston.

Disposed within the chamber *15* is a reciprocating piston *P'* of rectangular shape. As seen best in Figure 2, one outside dimension of piston *P'* is the same as the corresponding dimension 25 of chamber *15*, so that the side walls of the piston *P'* fit snugly against the inner side faces of the chamber *15*, but said piston *P'* is substantially shorter in its other dimension than the chamber 30 *15*, thus permitting reciprocation within said chamber. The outside length of the piston *P* in one of its dimensions, in this case its vertical dimension, is substantially equal to the corresponding inner dimension of the piston *P'*, the 35 other dimension of the piston *P* being substantially smaller, thus permitting snug reciprocal movement of the piston *P* within the piston *P'*.

It will also be seen from Figures 1 and 4 that the piston *P'* is preferably formed in two interlocking sections *50* and *50'* which are angular or L-shaped in cross-section and at various spaced points in their periphery are bored to seat helical springs *51* urging the members *50* and *50'* away from each other and into close cooperation with 40 faces *f* and *f'* of their respective adjacent frames *13* and *13'*. While this construction is not considered as absolutely requisite, since the piston *P'* may if desired be formed as an integral member, the described construction, from a 45 standpoint of convenience and economy, is considered desirable inasmuch as it substantially prevents passage of fluid without the necessity of such perfect machining as might unduly increase friction between the moving parts.

It will also be noted from Figure 2 that the piston *P'* is cut out at various spaced points along its outer side walls and along its inner top and bottom walls to provide pockets *53*. As seen best 50 in Figures 2, 7, and 8, these pockets accommodate channel-shaped sealing plugs *55* which are urged into position by means of spring clips *56* so as to seal the sliding surfaces between pistons *P* and *P'* against leakage of fluid.

As seen best in Figures 2 and 4, the members 55 *50* and *50'*, are beveled for a portion of their length to provide fluid pockets or cavities *57*.

The frame members *13* and *13'* are tapped as 60 at *58* to seat valve plugs *59*, these plugs seating against gaskets *60*. Each of said plugs may be bored as at *61* to receive a conduit *62* and is also provided with a chamber *63* housing a valve disk *64* which is urged against its seat as by means of a helical spring *65*, said spring being retained in position as by means of an annular nut *66*. 65 As seen clearly in Figure 1, the nut *66* may be

screwed into position in the plug *59* and may be provided with holes for a spanner wrench or other tool. A port *67* is provided in the frame *13* to permit communication between the valve chamber and the chamber *15* of housing *H*. 5

As seen clearly in Figure 1, the valves are for convenience arranged in opposite pairs, one of each pair being adapted for intake and the other for exhaust. While we have described only the intake valve, as shown in Figure 1, the construction and operation of the corresponding exhaust valve is substantially the reverse, valve disk *64'* being urged by a helical spring *65'* against an annular nut *66'*, which serves as the valve seat in this case. 15

As shown in Figure 3, four pairs of valves are provided in the embodiment shown. However, it will be obvious that this number may be modified.

The operation of the device just described is 20 as follows: Power is imparted to the shaft *16* from some suitable source, such as a motor, whereupon the crank *31* is given a rotary motion, carrying with it the piston *P*. This piston thus is given an absolute rotary motion; however, as it rotates, the piston *P* reciprocates within the piston *P'*, moving horizontally therein in the embodiment shown in the drawings. Said piston *P'*, on the other hand, is given a reciprocating motion within the chamber *15*, said motion being up and down in the particular embodiment shown in the drawings. 30

Considering the position of the parts as shown in Figure 2 as at 0° angularity, and assuming also that the shaft has a clockwise motion, as shown 35 in this figure, the subsequent relative positions of the two pistons *P* and *P'* and the housing will be substantially as represented in Figure 9 when the crank is at 90° to the position of Figure 2; the parts will be as represented in Figure 10 40 when the crank is at 180° to the position of Figure 2, and the parts will be as shown in Figure 11 when the crank is at 270° to the position of Figure 2.

It will be seen that in the position shown in 45 Figure 2, the pistons *P* and *P'* will have reached their limit of motion in the upward direction, thus completely exhausting the fluid through the upper exhaust valve. Continuing the motion in a clockwise direction, it will be seen that as the 50 parts move from the position of Figure 2 to that of Figure 9, fluid will be drawn into the space *70*, while fluid will be exhausted from the space *71* by the lateral motion of the piston *P*, and at the same time the fluid occupying the space *72* will 55 have been placed under compression. As the parts move from the position of Figure 9 to that of Figure 10, the fluid in the space *72* will be exhausted through the appropriate exhaust port while fluid will be taken into the space *71* by the 60 lateral movement of the piston *P*; at the same time fluid will have been drawn into the space *73* by the downward movement of the piston *P'*, to the maximum capacity of said space. As the 65 parts move from the position of Figure 10 to that of Figure 11, the lateral motion of the piston *P* will completely exhaust the fluid from the space *73*, fluid will have been drawn into the space *72* by the upward movement of the piston *P'* and by the same effect the fluid in space *70* 70 will have been placed under compression. Completing the cycle, in moving from the position of Fig. 11 to that of Fig. 2, fluid will be exhausted from space *70*, fluid will be compressed in space 75.

71, fluid will be sucked into space 72 and additional fluid drawn into space 73.

Referring now to Figures 12-15, inclusive, these views illustrate a valveless modification of our invention. As shown in Figures 12 and 13, this construction comprises a housing H' consisting of a pair of frames 113, 113', said frames being substantially similar and disposed opposite each other and maintained in spaced relation by a hollow frame member 114. These frames are secured in assembled relation as by means of bolts b and define a chamber 115.

Disposed within the chamber 115 is a reciprocable piston 117, said piston comprising a rectangular member which is substantially equal in one outer dimension to an inner dimension of the chamber 115 and substantially shorter in its other dimension, whereby said piston 117 may slidably reciprocate within said chamber 115. Said piston may be of any suitable construction, being either integral or built up of a plurality of members. In the embodiment shown, said piston is an integral member, being bored on opposite sides to provide ducts d_1 , d_2 for the passage of fluid. The sides 117^a and 117^b of said piston are provided with rectangular channels 120 spaced from the inner edges thereof for the seating of sealing bars 122, said bars being urged by resilient members such as wave springs 123 into close engagement with the inner faces of the frame members 113 and 113'. Said sealing bars are arranged on opposite sides of the piston 117 at the ends 117^a and 117^b, and are provided with terminal rectangular cut out portions which interlock at the corners, as shown at 124 (Fig. 12). As shown clearly in Figure 13, the bars 122 are effective to prevent passage of fluid from either side of the piston 117.

Mounted within the piston 117 is an inner piston 126, so constructed that one of its outside dimensions is substantially equal to an inside dimension of the piston 117, while its other dimension is substantially less than the corresponding dimension of the piston 117, whereby the piston 126 may slidably reciprocate within the piston 117.

Said piston 126 is provided with a pair of ducts 130, 130' disposed opposite each other. Said piston is also milled out adjacent its opposite ends to form cavities 132, 132' with which said ducts 130 and 130', respectively, communicate. It will also be apparent from Figure 13 that the cavities 132, 132' communicate, respectively, with the ducts d_2 and d_1 in the piston 117.

The piston 126, as shown clearly in Figure 15, is provided along its edges with longitudinal channels 135 and transverse channels 136 in which are seated longitudinal sealing bars 137 and transverse sealing bars 138, said bars being urged by resilient means such as wave springs 140 into close engagement with the inner surfaces of the frame members 113 and 113'. It will be obvious that said strips function to prevent passage of fluid past the piston 126.

As seen in Figs. 12 and 13, annular cavities are provided in the upper and lower faces of piston 126 for seating sealing rings 141.

In this embodiment there is provided a hollow shaft 142 which is mounted in the frames 113 and 113' as by means of threaded annular members 143 and lock nuts 144, an annular chamber 145 being provided for packing or the like, and the frame members 113 and 113' being provided with annular threaded bosses 146 for seating the journalling members 143. Ball bearings

or other suitable anti-friction devices 147 are also preferably provided.

Preferably formed integrally with the shaft 142 and arranged eccentrically thereon is a crank member indicated generally at 150. (See Fig. 14). Said eccentric is provided with a pair of pockets 151 and 151', said pockets being separated from each other by a wall 151^a. Pocket 151 communicates with bore 152 of the shaft on one side of the housing H' while pocket 151' communicates with bore 152' on the opposite side of the housing. Pocket 151 also communicates with an approximately segmental-shaped cavity 154 formed in the eccentric 150 while the pocket 151' communicates with a similarly shaped cavity 154' disposed on the opposite side of the eccentric from the cavity 154.

The eccentric 150 is also bored on opposite sides of its periphery, as clearly shown in Figure 12 to provide seats for plugs 157, said plugs being provided with axial cavities 159 for the seating of coil springs 160 urging said plugs toward the periphery of said eccentric. While these plugs have been shown in oppositely disposed pairs, it, of course, is understood that they may be arranged in other numbers and positions. Said plugs serve as seals to prevent passage of fluid between chambers 154 and 154' around the periphery of cam 150.

The eccentric 150 may be provided with a pair of peripheral channels 162 for the seating of sealing rings 163, it being understood that the plugs 157 are suitably shaped to seat said rings. It will be obvious that these rings function to prevent passage of fluid. Said eccentric is also preferably milled as at 165 for the seating of roller bearings 166 or other suitable anti-friction means.

It is believed that the operation of this embodiment of our invention will be apparent from the drawings. It will be understood, of course, that the two pistons move according to substantially the same principle as in the embodiment of Figs. 1-11. Assuming that bore 152' of the shaft 142 constitutes an inlet conduit and bore 152 an outlet conduit, when the parts are in the position shown in Fig. 12, fluid will have been completely exhausted through the duct d_2 and fluid will be under compression in the space 170 to the right of piston 126 (Fig. 12). Continued operation will result in movement of piston 126 to the right, whereby the fluid which has been compressed in space 170 will be exhausted through duct 138^a of said piston, from which it passes into the chamber 154, thence into chamber 151 of the eccentric and out through bore 152 of the shaft. At the same time this movement of piston 126 will draw air through bore 152' of the shaft, thence into chamber 151', from which it passes into segmental chamber 154' and out through duct 130^b of the piston 126, into space 171. Also, at the same time, the fluid in space 172 below piston 117 will be undergoing compression.

By the time the eccentric has reached the point where the edge 173 of segmental chamber 154 reaches the duct 130', the fluid within said space 172 will have undergone maximum compression and will then begin to exhaust through duct d_1 into opening 132, thence through duct 130' into the chambers 154 and 151 and on out through bore 152 of the shaft, as described above.

As the eccentric continues its rotation about the shaft the piston 126 will reverse its motion, after completely exhausting the fluid within the space 75

170 and will start to move toward the left (Fig. 12), thus beginning to compress the fluid within the space 171. It will be obvious that when the point 173 of the cam reaches duct 130^b the fluid 5 within the space 171 will be under compression and will then begin to flow out of said space 171 throughout duct 130^b into chamber 154 of the eccentric and ultimately out through the exhaust bore 152 of the shaft.

10 It is thought that the remainder of the cycle will be apparent from what has been described above.

Turning now to Figs. 16-19 inclusive, these views illustrate another valveless modification of our invention. This construction comprises frame members 213 and 213' secured as by bolts *b* in spaced relation by means of hollow frame member 214, said frame members constituting a housing H'', defining a chamber 215. Rotatably mounted 15 in said housing is a shaft 216, journaled in substantially the same manner as the shaft 142, shown in Figure 13.

Frame member 213 is drilled to provide an exhaust opening 220 which, if desired, may be threaded for connection with tubing or the like, while frame member 213' is similarly provided with an inlet opening 221.

Shaft 216 carries an eccentric disk or cam 224, best seen in Fig. 18. Said disk may be secured to the shaft in any suitable manner or may be integral therewith if desired; in the embodiment shown, said disk is keyed to the shaft as by means of key member 225.

Said eccentric disk, as is best understood from inspection of Figs. 18 and 19, is circular in cross-section and the cam surface thereof is incised to form a pocket 226 which extends only a portion of the way around the periphery of the disk, a channel 227 extending around the periphery of the disk 40 so as to connect the ends of the pockets 226, as clearly shown in Fig. 19. Spaced from the pocket 226 is a substantially similar pocket 226', a channel 227' substantially similar to the channel 227 and parallel thereto extending around the periphery of the disk so as to connect the ends of the pocket 226'. While channels 227 and 227' are shown of unequal width, they may be of the same width with satisfactory results.

The cam disk 224 is rotatably mounted in a circular opening of corresponding size formed in a rectangular piston 230. Said piston 230 is preferably skeletonized as much as possible by provision of balanced cut out portions 231, 231', in order to reduce weight as much as possible, and is also provided with ducts 232^a, 232^b, 232^c and 232^d. The ducts 232^a and 232^c are enlarged adjacent their ends to form elongated spaces 233^a and 233^c.

Formed also in piston 230 are chambers 235 and 235', said chambers being spaced longitudinally of the shaft so as to register respectively with the channels 227' and 227. As seen best in Fig. 17, the piston 230 is drilled to provide an opening 237 connecting the chamber 235 with the outlet opening 220 and an aperture 237' connecting the chamber 227 with the inlet opening 221.

There is also provided a rectangular piston 240 in which the piston 230 reciprocates. An inner dimension of the piston 240 is substantially equal to the corresponding outer dimension of the piston 230, while the piston 240 is substantially larger in its other dimension than the piston 230, thus permitting sliding reciprocation of piston 230 within piston 240. As shown best in Fig. 16, said piston 240 is provided with opposite ducts 242 and 75 242'.

It will be understood that the co-operating pistons 230 and 240 in this embodiment may, if desired, be of similar construction to the corresponding members shown in the other embodiments, so far as concerns sealing devices and other details. 5

In general, the operation of this embodiment is similar to that of the other embodiments described above so far as regards the action of the two rectangular pistons, the piston 230 being carried in a rotary motion with the cam or eccentric 10 224 and reciprocating within the piston 240 while the latter reciprocates within the chamber 215.

Considering the cycle beginning with the elements in position shown in Fig. 16, at this point piston 240 will have completely exhausted fluid 15 through duct 242, said piston being at its upper limit of movement. As the cam 224 continues its rotation clockwise (Fig. 16), piston 240 will begin to move down, drawing fluid through inlet opening 221 and thence into piston 230 via the bore 20 227' through pocket 235' and into chamber 227 of cam 224. As said cam continues its rotation, after it has reached a position where pocket 226 comes into registry with passage 232^a, fluid will flow through said passage and duct 242 into the 25 space above piston 240, which will be moving downwardly. At the same time, fluid will be exhausting from space 250 to the right of piston 230 (Fig. 16) through duct 232^b into chamber 226' of the cam, and thence through channel 227'. Since 30 this channel communicates with chamber 235 of piston 230, fluid will pass out through said chamber via outlet opening 237. Also at the same time, after the edge 253 of chamber 226' has passed the duct 232^c, fluid will exhaust from space 251 below 35 piston 240 by way of ducts 242' and 232^c into chamber 226' and thence out of the device, as described above.

It is believed that the remainder of the cycle will be clear from what has been described. 40

We claim:

1. In a device of the class described, a housing defining a rectangular chamber, intake and exhaust ports arranged in pairs on each side of said housing, a fluid-propelling member reciprocating within said housing for alternately drawing fluid into and expelling fluid from said housing, and a second fluid-propelling member reciprocating within said first-mentioned member for alternately drawing fluid into and expelling fluid from a space defined between said first member and said second member. 45

2. In a device of the class described, a rectangular piston, a second rectangular piston within which said first piston is reciprocable, a housing 55 within which said second piston is reciprocable, and means for imparting rotary motion to said first piston whereby fluid is alternately drawn into and expelled from the space between said first and second pistons and fluid is alternately drawn into and expelled from the space between said second piston and said housing, and an intake valve and an exhaust valve disposed on each side of said housing. 60

3. In a device of the class described, a pair of 65 frames arranged opposite each other and a similar frame disposed therebetween, said frames enclosing a rectangular chamber, a reciprocable fluid-propelling member disposed within said chamber and in contact with said opposite 70 frames, and means for preventing passage of fluid between said movable member and frames, comprising members carried by said reciprocable member having surfaces normally urged into contact with those of said frames. 75

4. In a device of the class described, a rectangular piston, a second rectangular piston within which said first piston is reciprocable, a housing forming a chamber within which said second piston is reciprocable, and a cam for imparting rotary motion to said first piston whereby fluid is alternately drawn into and expelled from the space between said first and second pistons and fluid is alternately drawn into and expelled from the space between said second piston and said housing, said cam having a cavity communicating with said chamber for passage of fluid. 10
5. In a device of the class described, a rectangular piston, a second rectangular piston within which said first piston is reciprocable, a housing forming a chamber within which said second piston is reciprocable, and a cam for imparting rotary motion to said first piston whereby fluid is alternately drawn into and expelled from the space between said first and second pistons and fluid is alternately drawn into and expelled from the space between said second piston and said housing, said cam having an inlet cavity and an exhaust cavity. 15
- 20
- 25
6. In a device of the class described, a pair of frames arranged opposite each other and a similar frame disposed therebetween, said frames enclosing a rectangular chamber, a reciprocable fluid-propelling member disposed within said chamber and in contact with said opposite frames, and means for preventing passage of fluid between said movable member and frames, comprising metallic strips disposed between said movable member and said frames, and resilient members urging said strips into fluid-sealing position, said movable member being recessed to house said strips and resilient members. 30
- 35
- 40
7. In a device of the class described, a pair of frames arranged opposite each other and a similar frame disposed therebetween, said frames enclosing a rectangular chamber, a reciprocable fluid-propelling member disposed within said chamber and in contact with said opposite frames, a second fluid-propelling member arranged to reciprocate within said first-mentioned member and at right angles to the motion thereof, means for imparting rotary motion to said second member, at least one of said members being formed
- of a pair of interlocking parts axially spaced, and means resiliently urging said parts into fluid-tight engagement with said opposite frames. 45
8. A device as defined in claim 3, wherein said fluid-propelling member is longitudinally recessed, L-shaped metallic strips disposed in said recesses in opposite pairs, and resilient members urging said strips into fluid-sealing contact with said opposite frames. 5
9. In a device of the class described, a rectangular piston, a second rectangular piston within which said first piston is reciprocable, a housing forming a chamber within which said second piston is reciprocable, and a cam for imparting rotary motion to said first piston whereby fluid is alternately drawn into and expelled from the space between said first and second pistons and fluid is alternately drawn into and expelled from the space between said second piston and said housing, said cam being provided with a pair of 20 non-communicating cavities, said pistons being provided with conduits communicating with said cavities at times within the cycle of movement of said device, and a hollow shaft for imparting rotation to said cam and communicating with the 25 cavities thereof, thus providing for inlet and exhaust of fluid to and from said chamber. 25
10. In a device of the class described, a rectangular piston, a second rectangular piston within which said first piston is reciprocable, a housing 30 forming a chamber within which said second piston is reciprocable, and a cam for imparting rotary motion to said first piston whereby fluid is alternately drawn into and expelled from the space between said first and second pistons and fluid is alternately drawn into and expelled from the space between said second piston and said housing, said cam being provided with non-communicating channels in the periphery thereof serving as intake and exhaust passages, re- 35 spectively, said pistons being provided with conduits communicating with said channels at times within the cycle of movement of said device, and conduits serving for the inlet and exhaust of fluid, respectively, to and from said chamber. 45
